UNITED STATES PATENT OFFICE.

FRANK ORTH, OF INDIANA HARBOR, INDIANA.

ROOF CONSTRUCTION FOR FURNACES.

1,265,493.

Specification of Letters Patent. Patented May 7, 1918.

Application filed April 18, 1916. Serial No. 91,876.

To all whom it may concern:

Be it known that I, FRANK ORTH, a citizen of the United States, residing at Indiana Harbor, county of Lake, and State of 5 Indiana, have invented certain new and useful Improvements in Roof Constructions for Furnaces, of which the following is a specification.

The present invention has to do with improvements in roof constructions for furnaces and also the method of making repairs in the same. The features of the invention are very well adapted for use in connection with open hearth steel furnaces, 10 although it will presently appear that said features are in no wise limited to this particular class of service.

In open hearth furnace practice it is found that generally the roof will burn away or 20 become dangerously thin in certain portions sooner than in other portions, so that it becomes desirable to be able to renew those portions which burn most rapidly. Also it is well understood that in order for an arch 25 roof to be self-sustaining with all portions of the roof material under compression, it is necessary for the so-called line of thrust to remain within the body of the roof material at all points throughout the arch.

30 Ordinarily the rear portion of the roof will burn away more rapidly than the front portion, or at any rate those portions of the roof opposite to the doors are generally found to burn away most rapidly.

35 In Letters Patent of the United States, No. 1,095,920, issued to me May 5, 1914, for improvements in arch construction for furnaces, and also in my Letters Patent of the United States, No. 880,910, issued to me

40 March 3, 1908, I have disclosed a type of roof construction in which there are provided transversely extending thrust ribs, the end portions of which are suitably supported against the spreading, and between which

45 ribs are placed the arch sections of roof. In the construction shown in the said Letters Patent, No. 1,095,920, the transverse ribs have their upper faces beveled, so that a wedge-shaped space is provided between the

50 upper portions of each pair of adjacent ribs. There are also disclosed in that Letters Patent certain replacement blocks of wedge-shaped or beveled formation adapted to be seated down between and to be supported by

55 the said upper portions of adjacent ribs, the

said replacement blocks having their end faces beveled to correspond with the beveling on the upper portions of the ribs.

When the replacement blocks are set between the beveled upper portions of the ribs 60 disclosed in the said Letters Patent, No. 1,095,920, a wedging action occurs by reason of which wedging action there is tendency to displace the ribs laterally, thereby throwing them out of line. Consequently, when 65 it is desired to effect a repair in a roof, by the use of wedge-shaped blocks seating down and resting solely upon the beveled faces of the upper portions of the ribs, such repair should be made in alternate sections 70 of roof, leaving the intermediate roof sections undisturbed until the said alternate sections have been repaired, after which the intermediate roof sections may be knocked out and repaired. In this way the tendency 75 toward the lateral displacement of the ribs may be reduced to a minimum, and the danger of cumulation of displacement at one end of the furnace may be largely obviated. Nevertheless, when using that type of rib 80 and repair block in which the repair blocks are supported solely by the said wedging action, the aforementioned difficulties cannot be entirely eliminated.

Furthermore, where the repair blocks are 85 supported solely by the aforementioned wedging action, they will necessarily seat down between the ribs low enough to bear firmly against the beveled portions of the adjacent ribs, and therefore the exact position 90 which they will assume necessarily depends upon the distance between the beveled upper portions. If the ribs are not all consecutively equi-distant from each other, or if the ribs do not lie absolutely parallel, or 95 if the repair blocks are not all of uniform dimensions, some of the repair blocks will seat down lower than others, so that an irregular repair patch will be the result. Not only will this produce a patch which is 100 unsightly in appearance, but it will produce the still greater disadvantage that the lower portions of some of the repair blocks will be much more exposed to the burning action than the other repair blocks, so that the 105 patch will not be as durable and satisfactory as would otherwise be the case.

One of the objects of the present invention is to provide a rib construction of such form that the repair blocks may be sup- 110

ported directly by the ribs without any wedging or thrusting action such as has previously been discussed. Also in this connection to so form the repair blocks that when 5 they are seated between the ribs, they will be directly supported without the necessity of any wedging action. Not only will this result in the elimination of the disadvantageous side thrust on the ribs, but it will also 10 result in uniformly supporting the repair blocks, so that the patch will be uniform and regular, the lower portions of all of the repair blocks of each patch coming together in a smooth unbroken surface. This will 15 also result in the advantage that in case the ribs are not all uniformly spaced, or in case they are not absolutely parallel to each other, or in case the repair blocks are not of uniform size, still a smooth regular patch 20 may be produced. Consequently, it will not be necessary when practising this feature of the invention to make use of the same amount of skill in the labor as would otherwise be necessary for the production of a 25 satisfactory patch.

Another feature of the invention has to do with the method of patching the roof. This method consists in the removal of selected burnt sections of roof and the substitution of repair blocks in said sections. 30 More particularly this feature of the invention consists in the removal of adjacent burnt sections of roof and the substitution of the repair blocks in said sections.

35 Frequently, some portions of a rib will be so burned away or reduced in depth as to make it desirable to repair the same by substituting blocks of greater depth in such portions of the ribs. Another feature of the 40 invention has to do with the proportioning of the original blocks in such size that they may be substituted into those portions of the ribs which it is desired to repair. This will result in an economy of material and 45 consequently in an economy in the cost of making the repairs.

Other objects and uses of the invention will appear from a detailed description of the same, which consists in the features of 50 construction and combinations of parts hereinafter described and claimed.

Referring to the drawings:

Figure 1 shows a front elevation of an open hearth furnace to which some of the 55 features of the present invention have been applied, a portion of the roof structure being broken away and the roof at this point being shown in section;

Fig. 2 shows a cross-section on enlarged 60 scale, taken on the line 2—2 of Fig. 1, looking in the direction of the arrows;

Fig. 3 shows a plan view of a section of roof having applied thereto the features of the present invention, and it shows by 65 means of dotted lines a section of roof

wherein it is desired to effect a repair, and wherein the repairs have been made by the substitution of the repair blocks;

Fig. 4 shows a longitudinal section, taken on the line 4—4 of Fig. 3, looking in the 70 direction of the arrows; and

Fig. 5 shows in detail, a modified form of rib and repair block embodying certain of the features of the present invention.

Referring to the several figures, the roof 75 is provided with a plurality of transversely extending arched ribs 6, the end portions of which are supported by buck stays 7, tie rods 8, channels 9, etc., in the manner set forth in the aforementioned Letters Patent 80 of the United States. Any other suitable means for supporting the end portions of the ribs may be adopted without departing from the spirit of the present invention.

Referring particularly to Figs. 3 and 4, 85 the intermediate roof sections 10 are set in between the lower portions of the ribs and are supported by them. These intermediate roof sections set between the lower portions of the ribs, engaging the side faces 90 of the blocks 11, to which blocks they may be cemented if desired. These original roof sections comprise the individual blocks 11, which, when new, form the lower surface of the roof at the point shown by the dotted 95 line 12 of Fig. 4, or the full line 12 of Fig. 2. After a period of operation the roof will have burned away on a somewhat irregular surface to the line 13 of Fig. 4. The extent of this burning will be irregular in 100 different portions of the roof, and as shown by the dotted line in Fig. 2 will generally be greater at the back side 14 of the roof than at its front side 15.

After the roof or any portion of the same 105 has become so thin as to make it desirable to effect a repair, the burnt blocks 11 will be removed and the repair blocks substituted. In Fig. 3 I have shown by the dotted lines 16 a section or portion of roof within 110 which it is desired to make a patch. This section of roof comprises portions of roof lying within the spans A, B and C, the patch illustrated not extending into the 115 spans D and E.

In order to place the patch in the burnt section of each span, the burnt blocks 11 are moved from the desired section and the repair blocks 17 are substituted. As shown in the several figures, each of the ribs is provided on each side with a transverse shoulder 18, said shoulder extending lengthwise of the rib, preferably at a point some distance below its upper edge 19. The upper portion 20 of the rib may be beveled or tapered according to the disclosure of Figs. 1, 2, 3 and 4 or it may be straight, as shown in Fig. 5. Nevertheless, in each case there are provided distinct supports on the side faces of the ribs, and in the construction 120 125 130

illustrated said supports take the form of the longitudinal shoulders 18. Each of the repair blocks 17 is provided with a lug or lip 21 adapted to seat squarely onto the shoulder 5 of the rib and be supported thereby. Consequently, the weight of the repair blocks is carried by the shoulders or other supporting means and not by any wedging action on the upper portions of the ribs. While it is true 10 that in Figs. 1, 2, 3 and 4 I have illustrated ribs which have their upper portions beveled, still it is intended that the major portion, if not all, of the weight of the repair blocks, shall be supported by the shoulders or other 15 supporting means.

Frequently, the repair blocks will be of somewhat larger size than the original roof blocks, although manifestly there is no necessity for using such a relationship. However, 20 in the several figures I have shown an arrangement in which there are originally three lines of original blocks between each pair of ribs, and in which the repair blocks are of such size that two of them will fully 25 occupy the space between the ribs when the repair is made.

It will also be observed from examination particularly of Fig. 4 that each of the original blocks 11 is of the same width as the 30 width of the ribs. There is no necessity that this ratio or relationship should be maintained, but when it is adopted the repair blocks may be conveniently built into new ribs or patches of ribs when desired without 35 changing the size of the blocks so substituted.

In proceeding to effect the repair, the section of roof wherein the patch is to be made is first selected. If the ribs and repair blocks 40 embodying the features herein disclosed are to be used, all of the roof sections may be removed from the portion of roof wherein the patch is to be made before commencing the substitution of the repair blocks. In this 45 case several adjacent or consecutive spans may be operated upon simultaneously, and in Fig. 3 I have shown patches as having been simultaneously inserted in the spans A, B and C. That is to say, the patches in all 50 of said spans may be made at the same time and not alternately. On the other hand, if desired, the alternate patching may be adopted and the patches may be inserted first in the alternate spans and afterward in 55 the intermediate spans. Therefore, as far as the method of repair is concerned, I contemplate the use broadly of the method which consists in first removing the desired portions of roof and thereafter inserting the 60 patches.

Examination particularly of Fig. 4 will show that in the arrangement illustrated therein, the replacement blocks are of slightly less width than the spaces between 65 the ribs whereon they are seated. By thus

proportioning the replacement blocks assurance is had that the said blocks will seat directly upon the shoulders of the ribs and be sustained thereby without any wedging action. Furthermore, by thus proportioning 70 the replacement blocks assurance will be had that the said blocks will be sustained by the shoulders without the necessity of spacing the ribs as accurately as would otherwise be necessary. Furthermore, the replacement 75 blocks will generally be made from silica or other material which has a comparatively high coefficient of expansion. By proportioning the replacement blocks in the manner just described so as to allow a slight clearance between the side faces of the replacement blocks and the ribs when the blocks are first inserted, the said blocks will be enabled to expand the necessary amount as their temperature rises without bringing 80 into play an undesirable side thrust on the ribs.

I claim:

1. In a heating furnace, the combination with the side thrust members, of a series of 90 transverse ribs spanning the width of the furnace and having their ends resting against the thrust members and supported thereby, the ribs arching over the body of the furnace, each rib being provided with 95 a longitudinal horizontal shoulder on each side and near its upper portion, the side faces of the ribs below said shoulders being vertical, and a series of replacement blocks between consecutive ribs and supported 100 thereby, each replacement block being provided in its upper portion with a horizontal shoulder adapted to seat directly on the rib shoulder and be fully supported thereby, and the side face of the block below 105 said shoulder being horizontal and resting squarely on the shoulder of the rib, substantially as and for the purpose specified.

2. In a heating furnace, the combination with the side thrust members, of a series of 110 arched transverse ribs spanning the width of the furnace and having their ends resting against the thrust members and supported thereby, the facing sides of adjoining ribs being provided with longitudinal 115 horizontal shoulders in their upper portions, the side faces of the ribs below said shoulders being vertical, and a series of replacement blocks between said ribs, each replacement block having in its upper portion a 120 horizontal shoulder adapted to rest squarely on the adjacent shoulder of a rib and be fully supported thereby, and the side face of the block below said shoulder being vertical, substantially as and for the purpose 125 specified.

3. In a heating furnace, the combination with a series of arched transversely extending ribs spanning the furnace, each rib being provided along its upper side face with 130

a horizontal shoulder, and the side face below said shoulder being vertical, of a series of replacement blocks between a pair of said ribs and supported thereby, each of 5 said blocks having in its upper portion a horizontal shoulder adapted to rest squarely on the rib shoulder, and the lower portion of the side face of the block being vertical.

to thereby eliminate any tendency toward creation of side thrust on the ribs by the 10 presence of the blocks, substantially as described.

FRANK ORTH.
